ATTACHMENT FOR WATER CLOSETS

Ferruccio Guidetti, Elmhurst, N. Y.

Application April 7, 1932, Serial No. 603,696

8 Claims. (Cl. 4-7)

This invention relates to plumbing appliances and more particularly refers to improvements in sanitary attachments for water closets and bidets of the type where a nozzle bearing arm is brought from an inoperative to an operative position for directing a jet of fluid against the body of the occupant of the seat for cleansing purposes.

A sanitary water closet attachment of the type to which this invention refers has been described and claimed in a co-pending application entitled Flushing arms for sanitary water closet attachments, Serial No. 516,858, (now matured into Patent No. 1,872,278 issued August 16, 1932), filed by me as co-inventor with Giuseppe Bon-tempi.

The arrangement described in said application comprises a supporting frame attached onto the rim of the bowl of the water closet or bidet by means of a clamping hook, a flushing or water delivery arm movable from an inoperative position directly above the rim of the bowl to an operative position within the bowl, means for displacing said arm between its two extreme positions and for causing rotation of same about its axis while it is so moved, and valve means for admitting cleansing fluid to said arm after it has reached its operative position.

When said arm is in its inoperative position it remains flat above the rim of the bowl, and when it is brought to its operative position the nozzle provided at the end of said arm comes to occupy a position within the bowl in which its axis remains on a vertical longitudinal plane passing through the center of the bowl and is upwardly inclined towards the rear of the bowl.

Water under pressure issuing from the nozzle will therefore be projected in an upwardly inclined direction towards the rear of the bowl. More particularly the direction of the fluid jet issuing from the nozzle will be such that the fluid under pressure will strike directly against the body outlet of the occupant of the seat in connection with which the cleansing operation is to be performed.

The flushing arm thus provided, when in its inoperative position, has its free or nozzle end resting above the rim at the rear of the bowl, the outer end of said arm being pivotally mounted upon the supporting frame at a point spaced laterally of the bowl, located on or in close proximity of a transversal axis passing through the center of the bowl.

The translatory or angular movement of the flushing arm in a horizontal plane is effected by

means of a cam-acting plunger member, while its rotatory movement about its own axis is effected by a cam-acting dog integral with said arm, striking a stop during the translatory movement of the arm.

I have found in practice that the arrangement forming the subject of said co-pending application is susceptible of improvement in various respects. Although it is preferable for the flushing arm to remain normally in a position where the water used to flush the bowl and residual matters cannot reach or contaminate it, and therefore it is desirable that the flushing arm remain entirely above the rim of the bowl and away from the cavity of the bowl, yet when the arm extends above the rear of the bowl, it is still exposed to contamination through carelessness of the user, and, therefore, further improvement in this direction is in order.

The position of the pivotal support of the flushing arm, pointed out above, is such that the supporting frame extends very materially from the side of the bowl.

In certain instances, this has proved to be a serious obstacle to the adoption of the improvement because of lack of sufficient clearance space between the bowl and the wall.

I have also found that the operation of the flushing arm by means of a plunger member imposes severe stresses upon the various parts of the mechanism and also entails various complications of design. The clamping hook attachment advocated in said application particularly has been found wanting in the matter of stability and rigidity, because of the stresses imposed upon it by the considerable downwardly directed force applied against the plunger member at a material distance from the point of attachment of the device onto the bowl.

Accordingly, the primary object of this invention is to provide a sanitary attachment of the character specified adapted to be secured onto the bowl of a water closet or bidet, in a manner which will cause said attachment to project but little in a lateral direction so as not to create undue difficulties in the matter of space requirements.

Another object is to provide in a sanitary attachment of the character specified a flushing or water delivery arm so arranged that when inoperative it rests above the rim and away from the cavity of the bowl at the side of the bowl, so as to occupy a position less likely to be exposed to the possible effects of carelessness or inadvertence.

A further object is to provide a device of the class specified where a flushing arm is caused to move from an inoperative position above the rim of the bowl to an operative position within the bowl, means of a simple and positive character for securing the device in position, said means being adapted for use in connection with practically all makes of bowls.

A still further object is to provide in a device of the class specified where the flushing arm is caused to move from an inoperative position above the rim of the bowl to an operative position within the rim of the bowl, operating means of an improved and simplified design whereby said arm can be caused to acquire a translatory and a turning movement through a single movement of the operating member, the operating member being rotatably mounted and being, therefore, smoother in action than an operating member of the plunger type.

Other objects and advantages of the present invention will more fully appear as the description proceeds and will be set forth and claimed in the appended claims.

My invention is illustrated by way of example in the accompanying drawings in which:

Fig. 1 is a plan view of a water closet equipped with a device embodying my invention;

Fig. 2 is a fragmentary vertical longitudinal section of said closet;

Fig. 3 is a side view in elevation of said device;

Fig. 4 is a view in elevation of said device from the inner side thereof;

Fig. 5 is a plan view in an enlarged scale of said device with the cover removed and the flushing arm broken in two parts;

Fig. 6 is a vertical section through line 6-6 of Fig. 5;

Fig. 7 is a vertical section through line 7-7 of Fig. 5;

Fig. 8 is a detail view in elevation of the valve controlling member; and

Fig. 9 is a cross sectional view thereof.

Referring to said drawings, 10 designates a toilet bowl of usual construction formed with a rim 11, surrounding the bowl cavity 12, and having a rear extension 13 carrying hinge bolts 14, 15, by means of which the seat 16 is attached to the bowl. The lower surface 17 of the seat is usually provided with rubber spacing feet 18 resting upon the edge of the rim 11, causing a clearance 19 to remain between the edge of the bowl and the lower surface of the seat.

The device illustrated comprises a supporting frame 20 upon which all the operating parts are mounted, said frame being surrounded by a shield 21 and a cover 22 and being connected by screws 23, 24, to the downwardly extending leg 60 of an L-shaped bracket 25 having a flat horizontal abutting arm 26 inwardly extending from the device transversely of the axis of the bowl, as shown in Fig. 1.

Said arm 26 is provided with two openings 27, 28 through which can be inserted the stems of hinge bolts 14, 15, in order to secure the device in position. The lower end of the downwardly extending arm 26 of bracket 25 is provided with an adjusting screw 25', as shown in Figs. 4 and 7, said screw resting against the side of the seat attachment extension and positively supporting the device against downward displacement.

As Fig. 1 clearly shows, when the device is thus secured in position it occupies the recessed

space 29 formed at the rear by extension 13 with the body of the bowl proper so that the body of the device does not project to an excessive extent laterally of a vertical plane tangent to the side of the rim of the bowl.

The flushing arm 30 extends inwardly in a direction inclined towards the front of the bowl from a pivotal attachment 31, and terminates with a curved portion 32, provided at the end with a nozzle 33, said curved portion remaining flat directly above the side portion 34 of the rim of the bowl when the flushing arm is in its inoperative position shown in Figs. 1, 2 and 5.

From said normal or inoperative position, the arm may be angularly displaced in a substantially horizontal plane about pivotal attachment 31 to the operative position shown at 30°, 32° in Figs. 1, 2, where its nozzle will occupy the position 33', where it is upwardly and somewhat rearwardly directed along the longitudinal vertical median plane of the bowl at a suitable distance beneath the plane of the seat 16, as shown in Fig. 2.

When the flushing arm is in its operative position and cleansing fluid is supplied thereto, the same will issue through the nozzle in a jet 35, which is upwardly and somewhat rearwardly directed so as to produce an effective cleansing action against the body of the occupant of the seat.

In order to make it possible for flushing arm 30 to rotate about its axis, the same is rotatably mounted upon a stem 36 outwardly projecting from the horizontal leg 37 of an elbow tubular piece 38, the vertical leg of which 39, is screwed onto the upper end of vertical pivotal member 31, as shown in Fig. 7.

When said pivotal member together with elbow member 38 is angularly displaced in a counterclockwise direction with respect to Fig. 5 about the axis of pivotal member 31, a slotted dog 40, integral with arm 30, is caused to engage a stationary pin 41, so that while the arm progresses towards the center of the bowl it is compelled to rotate about its axis in the direction shown by the arrow in Fig. 4. When the flushing arm is angularly displaced in the opposite direction, from its operative to its inoperative position, the opposite side of the slot 42 in slotted dog 40, will bear against pin 41 and will cause the arm to rotate in the opposite direction.

Vertical pivot 31 is rotatably mounted in a lug 43 upwardly projecting from body 20 and is provided with an axial opening 44, establishing communication between a passage 45 extending from a chamber 46 and elbow member 38. Said pivot 31 is retained in position in any suitable manner, for instance, by means of a nut 47.

Said pivot 31 also carries a plate 48 which is clamped between the bottom of part 39 of elbow member 38 and a nut 49. Said plate 48 constitutes the driven member of a Geneva type of control for causing the angular movement of pivot member 31 and elbow member 38, the driving member of said control being constituted by an arm 50 provided with a vertical stem 51, engageable at its upper end 52 by the hub 53 of an operating handle 54. Said stem is rotatably inserted through a bearing plate 55, which is attached by means of screws 56 onto a lug 57 vertically extending from the body 20.

The lower surface 58 of arm 50 is provided with a square recess within which is inserted the square upper end 59 of a vertical valve control-

ling member 60, which is rotatably mounted and which extends within and beyond chamber 46.

The lower end of said valve controlling member is enlarged to form a conical head 61 resting against a seat provided at the bottom of frame 20 and the end surface of said conical head is pressed in position end-wise by a plug 62.

By virtue of this construction when stem 51 together with arm 50 is rotated by means of handle 54, its rotation is transmitted to valve member 60, as will be understood. As stated, arm 50 acts as the driving member of a Geneva control and, therefore, is provided with an upwardly projecting pin 63, engaging a slot 64 formed in plate 48, and is furthermore provided with an upwardly projecting segmental member 65 adapted to engage and to register with a circular arc portion 66 of plate 48 and to retain said plate 48 in position after pin 63 has caused a predetermined angular movement of plate 48. Thus it will be seen that if stem 51 together with arm 50 is angularly displaced in a clockwise direction with respect to Fig. 5, plate 48 together with pivot 31 and elbow member 38, will be displaced a certain angle in a counter clockwise direction until segmental member 65 engages circular arc portion 66. When this position has been reached stem 51 and arm 50 can still continue to rotate in the same direction, but plate 48 will be securely restrained against further angular movement in either direction.

The rotation of stem 51 is effected against the action of a spring 67, which will return all the parts to their normal position shown in Fig. 5, as soon as handle 54 is brought from the position shown in full lines in Fig. 1 to the position shown in dotted lines, shown at 54', and during its movement the flushing arm is first brought from the position shown in full lines to the position shown in dotted lines in the same figure and then valves regulating the supply of cleansing liquid to chamber 46 are actuated by valve controlling member 60 to admit liquid to said chamber.

The device is shown equipped with two valves 68, 69, which are axially movable within glands 70, 71, said glands being connected respectively to sources of cold and hot water supply by means of tubes 72, 73.

The stems of said valves project within chamber 46 and during the rotation of valve controlling member 60 are acted upon to force said valves outwardly by radially extending cam-acting lugs 74, 75, with which valve controlling member 60 is provided. Said two lugs are preferably angularly displaced with respect to each other in relation to the axis of the valve controlling member, so as to operate the two valves in proper sequence.

Preferably said lugs are arranged so that during the movement of member 60, after the flushing arm has been brought to operative position, lug 74 will first bear against valve 68, causing the same to admit cold water to chamber 46, and as member 60 continues to rotate lug 75 will force valve 69 outwardly causing hot water also to be admitted to chamber 46. If member 60 is further rotated in the same direction, lug 74 will pass beyond valve 68, allowing the same to close, while lug 75 will continue to bear against valve 69 so that hot water only will be admitted to the chamber 46.

In this manner by regulating the extent of the angular movement of handle 54 it becomes

possible to regulate the temperature of the water admitted to the chamber 46 and supplied to the nozzle.

It is thus seen that by placing the device towards the rear of the bowl it becomes possible to cause the flushing arm to extend forwardly and to rest over the side portion of the rim of the bowl. In this position the arm is less likely to be inadvertently contaminated than if the arm were placed over the rear portion of the rim. The location thus advocated for the device has the further advantage of being in close proximity of the rear extension of the bowl, thus permitting of said device being secured in position by means of simple, reliable and positive attaching means, adapted to be retained in position by the hinge bolts with which the bowl is usually already equipped.

The constructional details of my invention may vary from those shown without departing from the inventive idea.

I accordingly reserve the right to carry my invention into practice in all those ways and manners which may enter, fairly, into the scope of the appended claims.

I claim:

1. An apparatus of the class described, adapted for use in connection with a closet bowl, comprising a support, an arm carrier mounted thereon so as to be angularly movable about a substantially vertical axis, a fluid delivery arm outwardly extending from said carrier, said arm being rotatable about its own axis at the point of attachment to said carrier, an actuating member angularly movable about a substantially vertical axis for causing angular movement of said carrier, and means cooperating with said arm for causing rotatory movement thereof when said carrier is displaced from one of its extreme angular positions to the other.

2. An apparatus of the class described, adapted for use in connection with a closet bowl, comprising a support, an arm carrier mounted thereon so as to be angularly movable about a substantially vertical axis, a fluid delivery arm outwardly extending from said carrier, said arm being rotatable about its own axis at the point of attachment to said carrier, an actuating member angularly movable about a substantially vertical axis, a section of a driven element of a Geneva gearing comprising a slot and an arc, integral with said carrier, a section of a driving element of the same gearing, comprising a pin adapted to engage said slot, and a segment adapted to engage and register with said arc, integral with said actuating member, means cooperating with said arm for causing rotatory movement thereof when said carrier is displaced from one of its extreme angular positions to the other, and means for operating said actuating member.

3. In apparatus of the class described, adapted for use in connection with a closet bowl provided with a rear seat attachment extension and hinge bolts inserted therethrough, a support, a fluid delivery arm mounted on said support so as to be movable from an inoperative position where it lies entirely above the side portion of the rim of the bowl, to an operative position where the outer end of said arm remains within said bowl, a strap extending from said support, adapted to cooperate with said hinge bolts for fastening said support onto said rear seat attachment extension, and adjustable means for

25

resting the lower portion of said support against the side of said extension.

4. An apparatus of the class described, adapted for use in connection with a closet bowl, comprising a support, an arm carrier mounted thereon so as to be angularly movable about a substantially vertical axis, a fluid delivery arm outwardly extending from said carrier, said arm being rotatable about its own axis at the point of attachment to said carrier, an actuating member angularly movable about a substantially vertical axis for causing angular movement of said carrier, means cooperating with said arm for causing rotatory movement thereof when said carrier is displaced from one of its extreme angular positions to the other, means for connecting said support to a source of water supply, and water delivery regulating means connected with, and actuated by, said actuating member.
5. An apparatus of the class described, adapted for use in connection with a closet bowl, comprising a support, an arm carrier mounted thereon so as to be angularly movable about a substantially vertical axis, a fluid delivery arm outwardly extending from said carrier, said arm being rotatable about its own axis at the point of attachment to said carrier, an actuating member angularly movable about a substantially vertical axis for causing angular movement of said carrier, means cooperating with said arm for causing rotatory movement thereof when said carrier is displaced from one of its extreme angular positions to the other, means for operating said actuating member, means for connecting said support to a source of water supply, and water delivery regulating means connected with, and actuated by, said actuating member.
6. An apparatus of the class described, adapted for use in connection with a closet bowl, comprising a support, an arm carrier mounted thereon so as to be angularly movable about a substantially vertical axis, a fluid delivery arm outwardly extending from said carrier, said arm being rotatable about its own axis at the point of attachment to said carrier, an actuating member angularly movable about a substantially vertical axis for causing angular movement of said carrier, means cooperating with said arm for causing rotatory movement thereof when said carrier is displaced from one of its extreme angular positions to the other, valve controlled means for connecting said support to a source of water supply, and a valve controlling member coaxial with, and actuated by, said actuating member.
7. An apparatus of the class described, adapted for use in connection with a closet bowl, comprising a support, an arm carrier mounted thereon so as to be angularly movable about a substantially vertical axis, a fluid delivery arm outwardly extending from said carrier, said arm being rotatable about its own axis at the point of attachment to said carrier, an actuating member angularly movable about a substantially vertical axis, a section of a driven element of a Geneva gearing comprising a slot and an arc, integral with said carrier, a section of a driving element of the same gearing, comprising a pin adapted to engage said slot, and a segment adapted to engage and register with said arc, integral with said actuating member, means cooperating with said arm for causing rotatory movement thereof when said carrier is displaced from one of its extreme angular positions to the other, means for operating said actuating member, means for connecting said support to a source of water supply, and water delivery regulating means connected with, and actuated by, said actuating member.
8. An apparatus of the class described, adapted for use in connection with a closet bowl, comprising a support, an arm carrier mounted thereon so as to be angularly movable about a substantially vertical axis, a fluid delivery arm outwardly extending from said carrier, said arm being rotatable about its own axis at the point of attachment to said carrier, an actuating member angularly movable about a substantially vertical axis, a section of a driven element of a Geneva gearing comprising a slot and an arc, integral with said carrier, a section of a driving element of the same gearing, comprising a pin adapted to engage said slot, and a segment adapted to engage and register with said arc, integral with said actuating member, means cooperating with said arm for causing rotatory movement thereof when said carrier is displaced from one of its extreme angular positions to the other, means for operating said actuating member, valve controlled means for connecting said support to a source of water supply, and a rotatable valve controlling member connected with, and actuated by, said actuating member.

FERRUCCIO GUIDETTI.
